UNITED STATES PATENT OFFICE.

JOSEPH L. WALKER, OF BATON ROUGE, LOUISIANA, ASSIGNOR TO THE K-D BARREL & HAMPER CO., OF BATON ROUGE, LOUISIANA.

MACHINE FOR MAKING BARRELS.

Application filed December 19, 1922. Serial No. 607,828.

To all whom it may concern:

Be it known that I, JOSEPH L. WALKER, a citizen of the United States, residing at Baton Rouge, in the parish of East Baton Rouge and State of Louisiana, have invented a new and useful Machine for Making Barrels, of which the following is a specification.

This invention relates to machines for making barrels, one of the objects of the invention being to provide a machine designed for rolling veneer with hoop and liner strips so as to produce a complete barrel.

Another object of the invention is to provide a machine of this character utilizing a collapsible drum or former the parts of which are mounted in a novel manner whereby all portions of the periphery of the drum can be shifted toward or away from the axis of rotation, thereby to collapse or to expand the drum.

Another object is to combine with the drum a novel arrangement of pressing rolls one of which cooperates with the drum to constitute means for feeding the stock around the drum.

A further object is to provide endless means for feeding the stock to the drum, said means being actuated by the drum pulling on the stock during the feeding operation.

A further object is to provide the feeding means with stock gripping means adapted to automatically release the stock during the completion of the feeding operation, thus to leave the feeding means stationary preparatory to forming another barrel.

A still further object is to provide improved means for positioning the bottom head of the barrel on the drum or former prior to the rolling of the stock about the drum.

Other objects are to provide improved means for removing formed barrels from the drum and to release the finished barrel from engagement by the pressing rollers during the removal of the barrel.

With the foregoing and other objects in view which will appear as the description proceeds the invention consists of certain novel details of construction and combinations of parts which will be hereinafter more fully described and pointed out in the claims, it being understood that various changes

may be made in the construction and arrangement of the parts without departing from the spirit of the invention as claimed.

In the accompanying drawings the preferred form of the invention has been shown.

In said drawings,

Figure 1 is an end elevation, parts being broken away.

Figure 2 is a horizontal section, the drum being shown in plan.

Figure 3 is a central vertical section, the drum being shown in elevation.

Figure 4 is an enlarged central longitudinal section through the drum, the stock, including the head, being shown in position on the drum.

Figure 5 is a section taken transversely through the drum and showing the endless feed table delivering stock thereto, only a portion of the table being illustrated.

Figure 6 is a section through a portion of the drum showing its segments collapsed.

Figure 7 is a section on line 7—7 Figure 6.

Figure 8 is a section on line 8—8 Figure 6.

Figure 9 is a side elevation of a portion of the feed table, parts being broken away.

Figure 10 is a transverse section through the feed table on line 10—10 Figure 9, the hoop strips being shown in position.

Figure 11 is a plan view, on a reduced scale of a portion of one of the chains of the feed table, the stave supporting springs being removed.

Figure 12 is a perspective view of one of the stave supporting springs.

Figure 13 is a perspective view of another form of stave supporting spring.

Figure 14 is a transverse section through one of the links carrying a hoop strip clamp, said section being taken on the line 14—14 Figure 9.

Figure 15 is an enlarged section on line 15—15 Figure 14, one end portion of a hoop strip being shown.

Figure 16 is a section through a head applying tool, the same being shown in position on one end portion of the drum with a head therein.

Figure 17 is a plan view showing the staves, hoop strips and liner strips assembled prior to being rolled into a barrel.

Referring to the figures by characters of reference 1 and 2 designate spaced frame

members in which is journaled the drum shaft 3, this shaft projecting across the space between the frame members and beyond the frame member 2 to a point adjacent to an opening 4 formed within a third frame member 5. The frame members are formed with standards 6 suitably connected and in two of these standards is journaled the main drive shaft 7 which, if desired, can be provided with a belt wheel 8. A gear 9 is secured to the shaft and meshes with a large gear 10 secured to a counter shaft 11 journaled in said standards. Another gear 12 is loosely mounted on the shaft 11 but is adapted to be coupled to the shaft by means of a clutch 13 feathered on the shaft and connected to an operating lever 14 or the like. Gear 12 meshes with a large gear 15 secured to shaft 3. Thus it will be seen that when gear 12 is coupled to shaft 11 motion will be transmitted from shaft 7 to the drum shaft 3.

Journalized within all of the standards 6 is a shaft 16 on which is loosely mounted a gear 17 meshing with a gear 18 secured to the drive shaft 7. A clutch member 19 is feathered on shaft 16 and is adapted to be shifted by a lever 20 or the like, thus to couple gear 17 to or uncouple it from shaft 16. On shaft 16 are secured several cams 21 each of which is adapted to actuate a stitching mechanism indicated generally at 22, these stitching mechanisms being located between two of the standards 6 or at any other points desired. An eccentric 23 is secured and rotates with the shaft 16 and is adapted to actuate a pitman 24 connected to a lever 25 fulcrumed on the frame member 1 as indicated at 26. A pawl 27 is pivotally connected to lever 25 and is supported on a ratchet wheel 28 secured to shaft 3. Thus when the pitman 24 is reciprocated the pawl 27 will be oscillated. This will cause the ratchet wheel 28 to rotate intermittently. Under normal conditions shaft 16 does not rotate but when gear 17 is coupled to the shaft the stitching mechanisms 22 will be actuated by cams 21 and during pauses in the stitching operations the ratchet wheel 28 will be rotated intermittently.

That portion of the shaft 3 located between the frame members 2 and 6 has a keyway 29 extending longitudinally thereof and provided with slidable keys 30 secured within the hub portions 31 of disks 32. Set screws 33 or the like are provided for holding the hubs 31 against movement longitudinally of the shaft but by loosening these set screws the disks can be brought to any desired positions relative to each other. Each disk is formed with openings 34 through which extend eccentric shafts 35, these openings being large enough to allow the shafts to rotate therein freely.

Disks 32 are located between end disks 36

secured to shaft 3 close to the frame member 2 and the free end of the shaft respectively. The ends of the shafts 35 are journaled in these end disks 36 and one end of each shaft 35 has a gear 37 meshing with a large gear 38 loosely mounted on the shaft 3. Gear 38 has a beveled portion 39 adapted to be engaged by an actuating gear 40 secured to a shaft 41 slidably mounted in a supporting bracket 42. Shaft 41 can be rotated by any suitable means, such as a crank 43 and can be moved longitudinally to bring gear 40 into or out of mesh with gear 39. A spring 44 can be employed for holding the two gears normally out of mesh. By shifting the gear 40 into mesh with gear 39 and then rotating shaft 41, gear 38 can be rotated and will thus rotate all of the gears 37 and cause all of the shafts 35 to rotate within the openings 34 and the disks 36.

Each disk 32 has laterally extending pins 45 extending through slots 46 provided adjacent the centers of segmental plates 47. One end of each of these plates is offset laterally as shown at 48 in Figure 7 and the other end of each of these plates is recessed as at 49 to receive the offset portions 48 of the next adjoining plate 47. Thus the ends of the segmental plates can lap and theselapping portions are formed with openings 50 and 51 respectively through which the eccentric shafts 35 extend. Each segmental plate has its outer marginal portion widened to form a rim 52 and these rims have upsetting plates 53 attached to them. Two or more longitudinal grooves 54 can be provided in the outer surface of each plate 53, these grooves constituting means for clinching the ends of staples driven into the grooves. On some of the segments the plates 53 extend across and laterally beyond the peripheries thereof. On other segmental members 47 longitudinal recesses are provided as shown at 55 in which are secured upsetting plates 56.

By mounting the segments 47 as described it will be apparent that the rotation of the eccentric shafts 35 will result in the bodily movement of the segment inwardly or outwardly to collapse or expand the barrel form or drum. As shown particularly in Figure 5 the openings 50 and 51 are peculiarly shaped so that the rotation of a cam shaft therein will first move the end of one segment 47 inwardly after which the near end of the other segment 47 will be moved inwardly. By having the rim portions of the segments projecting to form tongues 57 it will be apparent that it is thus possible to draw one segment inwardly relative to the tongue after which the other segment will be drawn inwardly so that the tongue will be brought to lapping position as shown in Figure 6. Reversal of the rotation of the shafts 35 will reverse the movement of the

segments. Thus a quick collapse or expansion of the former or drum can be effected by the bodily movement of all of the segments extending throughout the circumference of the drum or former.

For the purpose of supporting the shafts 35 between their ends, each of the shafts is extended through a roller 58 concentric with the axis of rotation of the shaft. These 10 rollers engage and are adapted to travel around a bearing disk 59 held to the shaft 3 by one of the keys 30 and having its periphery concentric with the shaft. By mounting the intermediate portions of the 15 shafts 35 in this manner said shafts are constantly held properly supported so as to resist the actions of the stitching mechanisms.

Supported longitudinally of the machine, 20 parallel with shaft 3, is a shaft 60 mounted in bearing blocks 61 slidably supported within the frame members 1, 2 and 5. A pressing roller 62 is carried by this shaft between the frame members 2 and 5 and a gear 63 is 25 also carried by the shaft and constantly meshes with a gear 64 secured to the shaft 3. The bearing blocks are yieldingly supported by springs 65 bearing against shiftable blocks 66 and engaging these blocks 66 30 are cams 67 carried by a shaft 68. A crank arm 69 or the like can be used for rotating shaft 68, thus to raise the bearing blocks relative to shaft 3 or allow the blocks to move away from the shaft. The movement 35 produced in this manner is very slight and will not be sufficient to interfere at any time with the proper meshing of the gears 63 and 64.

Pivoted connected to the frame members 40 2 and 5 are levers 70 in which are journaled trunnions 71 projecting from the ends of pressing rolls 72. These trunnions are engaged by spring pressed bearing blocks 73 45 slidable in the levers.

One pair of levers 70 located at any suitable point supports a shaft 74 on which are adjustably mounted rollers 75 adapted to 50 rotate in the same planes with the disks 32 and the segment carried thereby. By providing spaced rollers on one of these shafts, 74, sufficient clearance space is provided for a bracket 76 slidably mounted on a guide 77 55 suitably connected to the frame members 2 and 5. This guide may consist of parallel rods as indicated in Figure 1 and the bracket 76 can be secured in any desired manner to the rods after it has been adjusted to a predetermined position. A shaft 78 is journaled in bracket 77 and is provided 60 at one end with a cutter head 79 while its other end may be provided with a belt wheel 80 whereby the shaft can be driven continuously at a high speed by a motor, not shown, or any other suitable drive element.

The cutter head 79 is located adjacent the

disk 32 nearest frame member 2 where it will engage and chamfer the barrel stock at one end so as to flare the inner surface of said end to facilitate the insertion of a barrel head during the closing of a barrel 70 after being filled.

All of the levers 70 are slidably and pivotally connected at 81 to rings 82. These rings are connected by rods 83 to straps 84 mounted on eccentrics 85 secured to a shaft 75 86. This shaft is adapted to be rotated by means of a lever 87 or the like whereby the two rings can be rotated so as to simultaneously swing all of the levers 70, thereby to move all of the rollers 72 and 75 toward or 80 from the disks 32.

As shown particularly in Figures 3 and 5 the roll 62, which constitutes a feed roll is located beneath the disks 32 and close to an 35 endless feed table. This feed table includes spaced pairs of sprockets 88 on which are mounted endless chains 89 adapted to move over a support 90. The outer sides of the side chains are formed with outstanding 90 abutment ears 91 extending from the respective links and these ears are adapted to travel under retaining brackets 92 extending from the sides of the support 90. At regular intervals apart the links of the 95 chains are provided with transverse pins 93 mounted for rotation, each pin being journaled within the ear 91 of the link and also within an ear 94 extending from said link. To each pin is secured a gripping jaw 95 100 overhanging and cooperating with a transverse supporting bar 96 having an end abutment or shoulder 97. (See Figure 15.) Extending from one end of the pin 93 is a lifting finger 98 and a spring 99 bears downwardly on this finger so as to hold jaw 95 105 normally pressed toward the bar 96.

The jaws 95 on each chain are spaced apart a distance slightly greater than the length of the hoop strips to be fed to the barrel former and there are located on the support 90 tripping lugs 100 spaced apart a distance equal to the distance between every two adjoining fingers 98. The brackets 92 are located adjacent these lugs 100 so as to prevent the chains from lifting off 110 of the support 90 when the fingers 98 ride over the lugs 100.

A crank arm 101 may be connected to the shaft 102 on which one end portion of the feed table is mounted and by means of this crank the feed table can be actuated.

Each of the links of the chain has one or more side ledges 103 and to any of these ledges may be connected stave supporting springs 104 the free ends of which have upstruck ears 105. Each spring can be curved as shown in Figure 12 so as to overhang the fastened end thereof or, if preferred, each spring can be extended away from the attached end as shown in Figure 13. Springs 125 120

of different shapes are provided so that they can be adjusted accurately to properly engage staves of veneer of different standard widths. The ledges 103 are formed with 5 longitudinal slots 106 and the springs can be adjusted along these slots, as will be obvious.

That portion of the endless feed table supported close to the feed roll 62 is overhung 10 by a deflecting plate 107 and it is to be understood that other deflecting plates 108 can be located wherever desired to prevent the advancing ends of the stock from becoming hung on any portion of the machine 15 during the formation of the barrel.

Hingedly connected to the frame member 5 is a cross head 109 having any suitable means, such as a latch 110 for holding it in position across the opening 4 formed 20 within the frame member 5. A stub shaft 111 is journaled within the cross head 109 and extends from the center of a disk 112 in the periphery of which is formed an annular recess 113 provided with an upsetting 25 plate 114. The cross head 109 is adapted to be swung outwardly to leave the opening 4 unobstructed and thus allow a completed barrel to be removed from the machine through the opening. Short prongs 30 115 are provided at the free end of shaft 3 and are designed to engage and hold a barrel head when thrust against the end of the shaft.

Slidably mounted on that portion of the 35 shaft 3 between the frame members 1 and 2 are collars 116 and 117. The two collars are connected by links 118 and an actuating lever 119 is pivotally connected to the collar 117 and adjustably and pivotally connected 40 to a bracket 120 extending from frame member 2. Diverging arms 121 are fixedly connected to and extend from collar 116 and have parallel portions 122 slideable within the frame member 2. The free end of each 45 of these portions 122 has a head 123 and the heads are spaced apart diametrically a distance slightly greater than the diameter of the drum when collapsed or, in other words, this distance between the heads is substantially 50 equal to the diameter of the barrel when formed. Consequently longitudinal movement of the arms will result in the shifting of the former barrel longitudinally along the drum and into and through the 55 opening 4. Actuation of the heads 123 is effected by shifting lever 119 and causing it to pull through links 118 upon collar 116. When it is intended to use the machine herein described the disks 32 are adjusted 60 along the shaft 3 so that the segments carried thereby will be properly located to engage the formed barrel where the stitching operations are to take place. The sprockets 88 are also adjusted relative to each other

so as to properly engage and hold the hoop strips H. Springs 104 are adjusted to support the veneer staves S as shown particularly in Figure 5, the forward side edge of each stave resting on the adjacent ears 105 while the rear edges of the staves extend 70 under the adjacent ears 105 and rest on the free ends of the springs 104. Thus the staves will be supported in lapped relation by the springs of the endless feed table and will extend over the hoop strips H. The 75 back ends of the hoop strips extend under and are to be gripped by one set of jaws 95, as illustrated in Figure 15, these strip ends projecting rearwardly beyond the staves. The ends of the staves abut against the ears 80 91 and are thus held in alignment. The upper portion of the endless feed table is preferably of such length as to allow for the placing of two or more groups of stock, the stock of each group being sufficient to 85 make one complete barrel exclusive of the heads.

After the stock has been assembled as described the crank 101 is rotated so as to move the upper portion of the feed table 90 toward the drum. This movement will be sufficient to carry fingers 98 away from the tripping lug 100 adjacent the outer end of the supporting structure 90. Thus the jaws 95 will move downwardly under the action 95 of the springs 99 and grip the hoop strips thereunder as shown in Figure 15. This movement will also bring the advancing edge of the first stave and the front ends of the hoop strips between the roll 62 and the segments 47 carried by the disks 32. The operator then inserts liner strips L between the roll 62 and the segments 47 so that they will lie within the grooves or recesses 55 and 113. In the structure illustrated three 100 of these liner strips are fed to the machine one of the three, however, being received by the recess in the head 112 while the others are received by the recesses 55. 105

It might be stated that prior to the feeding of the stock to the drum as described a circular head B is applied to the end of the drum. This is done by first swinging the disk 112 to open position. A head B is then placed within a circular recess 124 formed 110 within the head 125 of an applying tool 126. The open face of this head is flared as shown at 127 and a handle 128 may be extended from the head. A plunger 129 is mounted for reciprocation in the head 125 115 and has a stem 130 slideable in the handle 128. After the head B has been placed in the tool shown in Figure 16 said tool is placed over the end of the drum which has been expanded to its maximum diameter by 120 means of the gears 39 and 40 and the eccentric 35 as heretofore explained. This action 125 will center the head B on the end of the

drum and by then thrusting plunger 129 violently against the center of the head B said head will be driven onto the prongs 115 which will thus hold the head B to the drum. The applying tool is then removed and the cross head 109 is swung back to position across the opening 4 so as to cause the disk 112 to clamp against the head B as shown in Figure 4. With the shock thus applied to the machine the shaft 78 is set in motion and shaft 68 is rotated so as to shift the roll 62 toward the drum and cause the stave and strip stock to be pinched between this roll and the drum. Lever 87 is actuated to swing levers 70 so as to position the rolls 72 close to the drum. The operator now shifts lever 14 so as to couple gear 12 to shaft 11 and thus transmit motion to shaft 3 and cause the drum to rotate. As both the drum and the roll 62 are driven positively the stock pinched therebetween will be fed between the drum and the rolls 72 until the advancing edge of the first stave is brought to position under the stitching mechanisms. The operator then uncouples gear 12 from shaft 11, thus stopping the rotation of the drum. He then shifts lever 20 to couple gear 17 to shaft 16. This will result in the actuation of the stitching mechanisms and also in the intermittent rotation of shaft 3 through ratchet 28 and pawl 27. Thus the drum will be given an intermittent rotation and the stitching together of the strips and staves will take place during the pauses in the rotation of the drum. It will be noted that the liner strips L and the hoop strips H are so positioned relative to each other that the same stitches will pass through them and through the staves. The upsetting plates located in the grooves in the segments 47 serve to clinch the fastening means.

The liner strips are longer than the circumference of the formed barrel and are designed to lap at their ends during the completion of the forming operation, these lapping ends being stitched together during the stitching of the other parts. Two of the liner strips will be positioned at opposite sides of the head B as shown in Figure 4.

It is to be understood that when the drum and roll 62 start to pull the stock into the machine motion is transmitted through the stock to the endless feed table which is thus actuated in the direction indicated by the arrow in Figure 9. As the last stave of the assembled stock passes between the drum and the roll 62 the fingers 98 of the jaws 95 gripping the hoop strips of the assembled stock will pass onto the tripping lugs 100 nearest the drum. Thus the fingers 98 will be lifted and jaws 95 moved out of engagement with the hoop strips H. This results in the disconnection of the stock from the table and the table will be brought promptly

to a stop. The table will remain stationary during the completion of the rolling of the barrel and while said operation is taking place some additional stock may be assembled on the table preparatory to being fed toward the drum.

After the rolling of the barrel has been completed the operator shifts lever 20 so as to disengage gear 17 from shaft 16. This will stop the actuation of the stitching mechanisms and the rotation of the drum. The operator then lowers roll 62 by turning crank 69 and also moves the rolls 72 away from the formed barrel by shifting lever 87 as heretofore described. Following this operation the disk 112 is swung away from the opening 4 so as to leave it unobstructed. By means of the gears 39 and 40 the eccentric rolls 35 are then actuated to collapse the drum throughout its circumference as shown in Figure 6. Lever 119 is then shifted so as to thrust the heads 123 against the end of the formed barrel whereupon said barrel will be pushed through the opening 4 and can be removed readily from the drum.

Following the removal of the barrel the foregoing operation can be repeated, the drum being first expanded to its maximum diameter, a head B clamped against one end of the drum, the rolls 62 and 72 properly positioned relative to the drum, the stock directed into engagement with the drum and the roll 62, and the mechanism then set in motion.

It might be stated that during the rolling of the drum the rapidly rotating cutter head 79 will chamfer the inner surfaces of the staves at the open end of the barrel so that a head can be inserted readily into the top of the barrel after it has been filled.

What is claimed is:

1. In a barrel making machine the combination with a former, of an endless carriage, means on the carriage for gripping hoop strips at one end, rotatable means cooperating with the former for gripping the hoop strips at the other end, and for causing it to conform to the former, and means for actuating the former and the rotatable means to bend the strips upon the former and actuate the carriage.

2. In a barrel making machine the combination with a former and a feed roll mounted for rotation, of an endless feed table, separate means thereon for supporting hoop strips and staves, means upon the table for gripping the hoop strips, and cooperating means on the table and adjacent thereto for disengaging the hoop strips from the table, said hoop strips constituting means for transmitting motion to the table from the former and feed roll.

3. In a barrel making machine the combination with a former and feed roll

mounted for rotation, of an endless feed table, a supporting structure therefor, yielding means for supporting staves in lapped relation upon the table, means for supporting hoop strips upon the table and below the staves, means upon the table for gripping the hoop strips at one end, means for actuating the table to direct the other ends of the hoop strips into engagement with the former and feed roll, means for actuating the former and feed roll to transmit motion through the hoop strips to the endless table, and cooperating means on the supporting structure and the table for releasing the hoop strips from the table.

4. In a barrel making machine the combination with barrel coiling means, of a feed table comprising endless chains, each chain including connected links, outstanding ears on certain of the links constituting stave abutments, ledges on the links, and means adjustably mounted on certain of the ledges for supporting staves in lapped relation.

5. In a barrel making machine the combination with barrel coiling means, of an endless table comprising parallel endless chains, laterally extending ledges on the links of the chains, yielding means adjustably mounted on the ledges for supporting staves in lapped relation.

6. In a barrel making machine the combination with barrel coiling means, of a feed table comprising side and intermediate endless chains, means adjustably connected to the chains for yieldingly supporting staves in lapped relation, means on the chains for supporting hoop strips under the staves, spring controlled jaws for engaging the hoop strips at one end, lifting fingers connected to the jaws, and means in the paths of the fingers for disengaging the jaws from the hoop strips during the actuation of the table.

7. In a barrel making machine a former including a shaft, members adjustably mounted thereon, segmental plates bodily movable on said members, parallel eccentric shafts extending through the end portions of said plates, and means for simultaneously rotating the eccentric shafts to shift the plates relative to the members to expand or contract the former throughout its circumference.

8. In a barrel making machine, a former including a shaft, member rotatable therewith, segmental plates connected to and movable radially of said members, said plates having abutting peripheral portions, eccentrics engaging the end portions of the plates, and means for simultaneously rotating the eccentrics to shift the plates toward the shaft and with the ends of their marginal portions in lapped relation.

9. In a barrel making machine a former

including members mounted for rotation, segmental plates radially movable on the members and having lapping ends, the marginal portions of the plates normally abutting to provide a continuous unbroken rim, eccentric shafts engaging the lapping portions of the plates, and means for simultaneously rotating said shafts to move the plates inwardly relative to each other to collapse the former and to bring the marginal portions of the segmental plates into lapped relation.

10. In a barrel making machine the combination with a shaft, of members mounted for rotation therewith, segmental plates slidably mounted on the members and having rim portions normally abutting at their ends to provide a continuous rim extending around the shaft, each of said rim portions having a projecting end constituting a tongue lapping the next adjoining plate, said plates being disposed in lapped relation at their ends, there being openings within the lapping portions of the plates, eccentric shafts mounted for rotation within the openings, and means for simultaneously rotating the shafts, each shaft cooperating with the walls of the openings in which it is mounted for successively moving the engaged end portions of the plates either inwardly or outwardly to collapse or expand the structure diametrically.

11. In a barrel making machine the combination with a collapsible former having liner strip receiving grooves, of means for clamping a head against the former, means for directing hoop strips, liner strips, and interposed staves to the former, and means for actuating the former to position the liner strips upon opposite faces of the head and for bending the staves and hoop strips around the head and liner strips.

12. In a barrel making machine the combination with barrel coiling means, of a feed table, means adjustably connected to the table for yieldingly supporting staves in lapped relation, means on the table for supporting hoop strips across the staves, jaws for engaging the hoop at one end, lifting elements connected to the jaws, and means in the paths of said elements for disengaging the jaws from the hoop strips during the actuation of the table.

13. In a barrel making machine the combination with a collapsible former, of means for clamping a head against the former, means for directing hoop strips, liner strips, and interposed staves to the former, and means for actuating the former to position the liner strips upon opposite faces of the head and for bending the staves and hoop strips around the head and liner strips.

14. In a barrel making machine the combination with a former, means for holding a head for rotation with the former, and

means for directing hoop strips, liner strips and interposed staves to the former, of means for actuating the former to position the liner strips upon opposite faces of the head and for bending the staves and hoop strips around the head and liner strips.

5 In testimony that I claim the foregoing

as my own, I have hereto affixed my signature in the presence of two witnesses.

JOSEPH L. WALKER.
